UNITED STATES PATENT OFFICE.

JAMES H. RAND, JR., OF TONAWANDA, AND LOUIS C. BROECKER, OF BUFFALO, NEW YORK; SAID BROECKER ASSIGNOR TO SAID RAND, JR.

RECORD TRAY OR CONTAINER.

Application filed February 2, 1924. Serial No. 690,233.

To all whom it may concern:

Be it known that we, JAMES H. RAND, Jr., and LOUIS C. BROECKER, citizens of the United States, residing at Tonawanda and

5 Buffalo, respectively, in the county of Erie and State of New York, have invented a new and useful Improvement in Record Trays or Containers, of which the following is a specification.

10 This invention relates to improvements in trays, slides or devices adapted to support or contain index cards, card-holders or other record-bearing matter. More particularly the invention relates to devices of this 15 character which are formed of sheet metal.

The cards or card-holders are sometimes provided with flaps or tongues whereby an edge of one card or holder may be inserted beneath the flap or tongue of an adjacent 20 card or holder to maintain them in overlapping, nested arrangement with their free edges exposed or projecting one beyond another.

Some of the trays or supports have heretofore been provided having a back or bottom part on which the record-bearing cards or matter are adapted to rest, and side or flanges or parts adapted to engage ears or side portions on the cards for retaining 25 them in their overlapping, nested arrangement and permitting sliding movement thereof on the tray, while preventing their transverse movement or displacement.

Followers or members are also used which are adapted to engage one or more of the cards or holders for holding them in proper position and nested relation longitudinally of the tray. These followers are usually arranged adjacent one end, for instance the 40 front end, of the tray, and are adapted to compress the nested cards so that they are forced towards the opposite or rear end of the tray, the last card or card-holder at such end being in engagement with a part 45 of the tray such, for example, as the fixed end wall. In some cases this end wall is bent or flanged to overhang the end of the last card, to prevent this edge from buckling to an extent which would cause the parts 50 of the card or holder to become detached from engagement with the side flanges of the tray, and also to prevent unintentional or unauthorized removal of the cards, while in operative position. This arrangement, 55 however, is objectionable for the reason that

the sharp bent-over edge of the back wall tends to crease or damage adjacent cards when such cards are swung to exhibit their under faces.

Trays or supports of this sort have also 60 been provided with hinged cover plates swinging on relatively fixed pivots or parts at the rear end of the tray and adapted to lie on the upper face of the rear or last card of the series to cover and protect the 65 exposed record matter thereon. These cover plates, as at present provided, are usually in the form of thin, flat sheets of metal or other suitable material, and it has been found that, owing to the fact that such 70 plates bear over their entire surface on the card or cards therebeneath, a relatively great amount of friction and wear is present when the cards are raised or lowered in use, due to the relative movements between the cover plate and the cards, resulting in an amount of wear sufficient to 75 destroy or deface the record matter and render the card useless.

One of the objects of the present invention is to provide a tray or support of this character with improvements, including a removable back stop or retaining member having a part adapted to overhang and retain the edge or edges of the card or cards 85 at that end of the tray opposite to the follower to prevent access to or manipulation of such edges while the follower is in operative position.

Another object is to provide an improved 90 cover plate of the sort mentioned, which is also adapted to be readily applied to or removed from the tray, and which is constructed so as to assist in maintaining the cards in proper position in the tray or container by its weight, while nevertheless being adapted to be readily moved with or by the cards when the cards are in use, with the minimum of frictional contact.

Still another object is to provide a combined removable back stop and cover plate having interengaging parts adapted to maintain said back stop and cover plate in proper operative position on the tray, said parts being adapted to permit the cover 100 plate to move relatively to the back stop member without marring or injuring the finish thereon and which will reduce the friction between these parts to a minimum.

Another object is to arrange the card-

engaging part of the cover plate so that the pressure exerted thereby on the card will be distributed through a relatively great number of the superimposed cards and thereby form a secondary compression member to assist in maintaining the cards within their intended limits on the tray.

Other objects of the invention are to improve card index trays or devices in the other respects hereinafter specified and claimed.

In the accompanying drawings:

Fig. 1 is a plan view of a card index tray or slide provided with the improvements embodied in this invention.

Fig. 2 is a longitudinal sectional elevation thereof on line 2—2, Fig. 1.

Fig. 3 is a fragmentary side view partly in section on an enlarged scale, showing a cover plate adapted for use with cards of a different size to those shown in Figs. 1 and 2.

Fig. 4 is an enlarged transverse section of the tray or slide on line 4—4, Fig. 1, showing the back stop and cover plate.

Fig. 5 is a similar view of the tray on line 5—5, Fig. 6, with the back stop and cover plate removed.

Fig. 6 is a longitudinal section of the rear end of the tray as arranged in a cabinet.

Fig. 7 is a similar view of the tray, showing the action of the cover plate when the adjacent cards are lifted to expose the cards beneath.

Fig. 8 is a fragmentary perspective view of a portion of one side of the tray showing one of the apertures in which the cover plate is journaled.

Fig. 9 is a similar view of the back stop detached.

In the drawings, a card index tray is shown which includes a bottom or back portion A, side walls B, and overhanging flanges C spaced from and connected to the side walls B by a top flange c. The lower or free edges of the flanges C are spaced from the back portion A of the tray so as to permit the insertion therebeneath of the tongues or portions D on the cards or holders E, whereby the cards are maintained in sliding engagement with the tray. The tray is also provided with a rear wall B' preferably formed of a separate sheet metal stamping and having a bottom flange b adapting it to be secured, as by spot welding, to the rear of the back or bottom A of the tray. The trays are usually provided with a hinged or pivoted tail piece, as at A', adapting the trays when used in a cabinet to be pulled out of the cabinet to expose their contents, while the tail piece will engage a part at the front of the cabinet to prevent the disengagement of the tray from the cabinet. The tail piece is preferably

hinged as at a to lugs a' extending rearwardly beyond the rear wall B' of the tray, the lugs being preferably secured to the tray between the flange b and the bottom A.

The card or card-holders E are preferably provided with flaps or portions F at one edge, whereby an edge of one card may be inserted beneath the flap of an adjacent card to maintain them in overlapping nested arrangement, with their free edges exposed or projecting one beyond another, as shown in Figs. 1 and 2.

A follower or primary compression member, see Fig. 2, comprising a card-engaging plate G and an operating part or stem g adapted to engage a fixed part of the tray to hold the part G in engagement with one or more of the cards, is preferably arranged as shown, at the front end of the tray, so that the part G is engaged under the flap F of the last card at that end of the tray. The follower is adapted to compress the nested cards and force them towards the opposite end of the tray or towards the rear wall B' to maintain them in the desired overlapping arrangement. For this purpose the stem g extends out through a hole in the front wall of the tray, and is provided with a notch g' engageable over the edge of the wall at said opening. The card holders have more or less natural elasticity, and when not engaged by the follower plate G, tend to spread apart slightly and therefore occupy more space lengthwise of the tray than when forcibly held in interlocking, nested position. The distance between the card holder engaging edge of the plate G and the notch in the stem g is such that considerable pressure must be applied against the end of the stem to compress the card holders towards the rear wall of the tray before the notch can be engaged with the tray wall. After this is done, the stem will be maintained in locking engagement with the tray by the outward pressure or resistance offered by the holders. To release the card holders, an upward movement is given to the outer end of the stem to release the notch from the front wall, whereupon the cards will separate slightly and force the follower outwardly until the holders assume their loose or released position.

A follower or member of any other form, adapted to the purpose stated, may be used. The tray, as above described, is of known form, and of itself forms no part of the present invention. Any other tray of suitable form may be used.

The invention contemplates the provision of a back stop or member preferably arranged at the rear of the tray against which the rearmost of the series of cards, compressed by the follower G, may abut, said back stop being releasably maintained on the tray and having a part adapted to

prevent the unauthorized or accidental releasing of the rear edge or edges and removal of the adjacent cards or cardholders.

- 5 The back stop shown in the drawings comprises a member 20 having a top plate or portion 21, a depending rear flange or part 22 and an integral rearwardly directed, substantially V-shaped recessed part 23 extending from and beneath the front edge of the plate 21. The back stop is arranged transversely on the tray between the flanges C, with the recess 23 disposed so as to receive the back edge of the rear card, which 10 will be forced snugly into the bottom thereof by the pressure of the follower G. The upper portion of the part 23 thus overhangs the edge of the card and prevents the removal of this and adjacent cards while they 15 are in operative position, and at the same time presents no abrupt or sharp edge to wear the card or holders. Means are provided for releasably maintaining the back stop 20 in operative position on the tray.
- 20 25 In the drawings, the back stop is positioned with its rear depending flange 22 abutting against the rear wall B' of the tray, the free edge of the flange preferably being in engagement with the bottom flange b of the 30 wall, while the lower edge 24 of the recessed part 23 engages one or more fixed lugs or parts 25 extending upwardly from the bottom A of the tray. These lugs 25 prevent movement of the back stop away from the 35 rear wall B', while nevertheless permitting the ready insertion and removal thereof from the tray, which may be accomplished by grasping the back stop at the front of the upper plate portion 21 and tilting the 40 back stop so as to disengage the edge 24 from the lugs 25. Any other suitable means may be provided for releasably holding the back stop in contact with the back wall of the tray.
- 45 50 As shown in Fig. 2 of the drawings, the body portions of the cards or holders E, in their nested and overlapping position, form a relatively thick pack, the upper face of which, formed by the free edges of the cards, is adjacent the plane of the tops c of the side walls B of the tray, while the face of the rear card is exposed. Some of these cards, in use, become slightly buckled or warped and tend to increase the thickness 55 of the pack to an extent sufficient to cause the top face of the pack or portion thereof to extend above the top of the side walls, and when the tray is used in a cabinet and otherwise, this increased thickness is very 60 undesirable, as the cards would rub against the partitions or other parts of the cabinet with resultant wear and defacement. To eliminate this, and to prevent wear and defacement of the record matter on the exposed rear card, a top plate or member is

provided having improved means for securing it on the tray and for maintaining the thickness of the pack of cards and holding them compressed within the desired limits, and protecting the record matter on the rear 70 card while nevertheless being adapted to swing freely on the tray to permit the cards to be manipulated, as desired.

The cover plate, which also serves to compress the cards or holders, is preferably constructed and mounted as shown in the drawings and comprises a plate or body portion 30 of approximately the size of the card or holder used in the tray and adapted to extend over and conceal the record matter on 80 the rear card, leaving only the free edge of this card exposed. The back edge of the plate 30 is preferably bent or rolled to form a tubular bearing or journal portion 31, the opposite ends of which extend beyond the 85 side edges of the plate 30 and form bearing pintles or journals 32. The card-engaging flanges C are recessed as shown at 33 for the reception of the journals 32 which are adapted to seat in the closed ends of the 90 recesses, these being positioned so as to permit the cover plate to lie substantially parallel with and slightly below the top edges of the tray, see Fig. 2. The cover plate journals are conveniently maintained 95 in operative position in the recesses by any suitable means, but preferably, as in the construction shown, by a part or parts of the back stop 20. The cover plate may be inserted in the tray by extending the bearing 100 portion 31 diagonally across the tray so as to bring the pintles 32 beneath the flanges C, after which the plate may be straightened to bring the pintles into register with the recesses 33. The back stop is then 105 slipped into position beneath the bearing portion 31, thus forcing the pintles 32 into the inner ends of the recesses. The top flange 21 of the back stop is preferably formed 110 with one or more bosses 35 having rounded 115 faces which contact with and form bearing surfaces for the journal portion 31, thus forming an antifriction bearing permitting free swinging or pivotal movements of the cover plate relatively to the back stop, and 120 as these parts contact only on the rounded faces of the bosses 35, the friction is reduced to a minimum and the finish of the back stop and of the plate is not marred, as would be the case if the journal portion contacted 125 throughout its length with the back stop. The described location of the cover plate journal also materially assists in maintaining the back stop in position on the tray 130 as no upward movement thereof is possible owing to the engagement of the pintles 32 with the inner ends of the recesses 33, nevertheless the back stop and cover plate are easily inserted or removed as desired. There is thus provided a combined detach- 135

able back stop and cover plate, both of which are readily applied to or removed from the tray, when desired, but which are positively maintained in operative position without danger of becoming accidentally detached or displaced when the tray is in use.

The cover plate 30 is formed with a part, preferably in the shape of a transverse bead 10 or depression 36 adjacent its free edge, as shown, which bead is adapted to contact with the outer end of the last card at a point such that the weight of the plate is distributed through the pack of cards to hold them 15 compressed within the desired limits, at the same time the bead forms an antifrictional contact with the card to prevent the body of the cover plate from engaging and rubbing the surface of the card and defacing 20 the record matter thereon.

The cards may be readily lifted, as shown in Fig. 7, the bead 36 sliding freely on the card with the minimum of friction. To facilitate lifting the cover plate to permit 25 an examination of the date on the card beneath, the free edge of the cover plate is inclined as at 37 so that it is out of contact with the edges of adjacent cards thereby allowing its ready manipulation.

If desired, the top edge of the back wall B' of the tray may be flanged as shown at 38 to form a rest for the cover plate when moved to the position shown in broken lines in Fig. 7, so that the rear faces of the cards 35 may be viewed and entries made thereon, if desired.

The described construction of the cover plate makes it possible to adapt these plates to cards of varying lengths, as shown in full 40 and dotted lines in Fig. 3, as cover plates are readily interchangeable.

Where it is desired to insert cards of greater or less length on a given tray, a cover plate corresponding in length to the 45 length of card used is selected, thus providing adequate protection for the record matter on the exposed last card, regardless of the size of card used.

We claim as our invention:

50 1. In a record device adapted to support a series of record-bearing members in predetermined arrangement, the combination of a part providing a support for said record-bearing members, means for engaging one end of said series of record-bearing members for limiting movement of said record-bearing members in one direction on said support, said means being removably mounted on said support, and movable means for applying pressure to the opposite end of said series of record-bearing members.

2. A record device having a part for supporting a series of record-bearing members in predetermined overlapping relation substantially parallel with said supporting part,

means for engaging one end of said series of record-bearing members for limiting movement of said record-bearing members in one direction on said support, said means being removably mounted on said support, and movable means for applying pressure to the opposite end of said series of record-bearing members.

3. In a record device adapted to support a series of record-bearing members in predetermined arrangement, the combination of a part providing a support for said record-bearing members, means for engaging one end of said series of record-bearing members for limiting movement of said record-bearing members in one direction on said support, said means being removably mounted on said support and having a part adapted to overhang a portion of one of said record-receiving members whereby said record-receiving member is maintained against unintentional removal from said supporting part, and movable means for applying pressure to the opposite end of said series of record-bearing members.

4. In a record device, a record-supporting part for maintaining a series of record-receiving members in predetermined arrangement substantially parallel to said supporting part, a stop member for engaging one of said record-receiving members to limit movement of said record-receiving members in one direction on said supporting part, a plate member adapted to cover the record-receiving portion of said record-receiving member, said stop member and said plate member being detachably mounted on said support, and means for applying pressure to said series of record-receiving members to hold said record-receiving members against said stop member.

5. In a device of the character described, means for supporting a plurality of record-receiving members in predetermined overlapping relation, and a metal guard plate 110 for covering the record-receiving portion of the uppermost of said record-receiving members, and means for detachably mounting said guard plate on said device.

6. In a record device adapted to support a series of record-bearing members in predetermined arrangement, the combination of a part providing a support for said record-bearing members, means for engaging one end of said series of record-bearing members for limiting movement of said record-bearing members in one direction on said support, said means being removably mounted on said support and having a part into which a portion of one of said record-receiving members may enter, and movable means for compressing said series of record-receiving members, whereby said record-receiving member is held against said part on said removably mounted means, so that said rec-

ord-receiving member is maintained against unintentional removal from said supporting part.

7. In a record device adapted to support a series of record-bearing members in predetermined arrangement, the combination of a part providing a support for said record-bearing members, means for engaging one end of said series of record-bearing members for limiting movement of said record-bearing members in one direction on said support, said means being removably mounted on said support, movable means for applying pressure to the opposite end of said series of record-bearing members, and means on said support for engaging said removably mounted means, whereby said removably mounted means is maintained in operative position on said record device.

8. In a record device, a record-supporting part for maintaining a series of record-receiving members in predetermined arrangement substantially parallel to said supporting part, a stop member for engaging one of said record-receiving members to limit movement of said record-receiving members in one direction on said supporting part, a plate member adapted to cover the record-receiving portion of said record-receiving member, said stop member and said plate member being detachably mounted on said support, and means for applying pressure to said series of record-receiving members to hold said record-receiving members against said stop member, said stop member having means for engaging said plate member and releasably maintaining said plate member on said supporting part.

9. In a record device, a record-supporting part for maintaining a series of record-receiving members in predetermined arrangement substantially parallel to said supporting part, a stop member detachably mounted on said record device for engaging one end of said series to limit movement thereof in one direction, a movable primary compression member adapted to engage the opposite end of said series to limit the movement thereof in the opposite direction, and a secondary compression member detachably mounted on said record device and having a part adapted to normally engage and compress said series of record-receiving members in a direction substantially perpendicular to the direction of compression of said primary compression member.

10. In a record device, a record-supporting part for maintaining a series of record-receiving members in predetermined arrangement substantially parallel to said supporting part, and having means at opposite sides thereof for limiting movement of said series transversely of said supporting part, a stop member detachably mounted on said

record device, a movable compression member on said record device, said stop member and said compression member being adapted to respectively engage opposite ends of said series of record-receiving members to limit movements of said series in opposite directions longitudinally of said supporting part, and means detachably mounted on said record device for normally compressing said series of record-receiving members in a direction substantially perpendicular to said supporting part.

11. In a record device, a record-supporting part for maintaining a series of record-receiving members in predetermined arrangement substantially parallel to said supporting part, and having means at opposite sides thereof for limiting movement of said series transversely of said supporting part, a stop member detachably mounted on said record device, a movable compression member on said record device, said stop member and said compression member being adapted to respectively engage opposite ends of said series of record-receiving members to limit movements of said series in opposite directions longitudinally of said supporting part, and means detachably mounted on said record device for normally compressing said series of record-receiving members in a direction substantially perpendicular to said supporting part, and said compression means being adapted to cover and protect the record-receiving portion of one of said record-receiving members.

12. In a record device, a record-supporting part for maintaining a series of record-receiving members in predetermined arrangement substantially parallel to said supporting part, and having means at opposite sides thereof for limiting movement of said series transversely of said supporting part, a stop member detachably mounted on said record device, a movable compression member on said record device, said stop member and said compression member being adapted to respectively engage opposite ends of said series of record-receiving members to limit movements of said series in opposite directions longitudinally of said supporting part, and a plate member detachably mounted on said record device adapted to cover and protect the record-receiving portion of one of said record-receiving members, said plate member having a part adapted to engage said series of record-receiving members to resist and limit movements thereof in a direction substantially perpendicular to said supporting part.

13. In a record device, a record-supporting part for maintaining a series of record-receiving members in predetermined arrangement substantially parallel to said supporting part, a stop member for engaging one of said record-receiving members to

limit movement of said record-receiving members in one direction on said supporting part, means for applying pressure to said series of record-receiving members to hold said series of record-receiving members against said stop member, and means on said supporting part for engaging opposite sides of said stop member to prevent movement of said stop member and 15 maintain said stop member in operative position on said record device.

14. In a record device, a record-supporting part for maintaining a series of record-receiving members in predetermined arrangement substantially parallel to said supporting part, a stop member for engaging one of said record-receiving members to limit movement of said record-receiving members in one direction on said supporting 20 part, a plate member adapted to cover the record-receiving portion of said record-receiving member, said stop member and said plate member being detachably mounted on said support, means for applying pressure 25 to said series of record-receiving members to hold said record-receiving members against said stop member, means on said supporting part and on said plate member for engaging said stop member to maintain 30 said member in operative position on said record device.

15. In a record device, a record-supporting part for maintaining a series of record-receiving members in predetermined arrangement substantially parallel to said supporting part, a transverse back wall on said supporting part, a stop member for engaging one of said record-receiving members to limit movement of said record-receiving 35 members in one direction, means for applying pressure in the opposite direction to hold said record-receiving members against said stop member, and means on said supporting part for holding said stop member in engagement with said back wall to maintain said member in operative position on said record device.

16. In a record device, a record-supporting part for maintaining a series of record-receiving members in predetermined arrangement substantially parallel to said supporting part, a transverse back wall on said supporting part, a stop member for engaging one of said record-receiving members to limit movement of said record-receiving members in one direction, means for applying pressure in the opposite direction to hold said record-receiving members against said stop member, a plate adapted to 50 cover the record-receiving portion, of one of said record-receiving members, means on said supporting part for holding said stop member in engagement with said back wall, and means on said plate member 55 adapted to hold said stop member in en-

gagement with said supporting part whereby said stop member is maintained in operative position on said record device.

17. In a record device, a record-supporting part for maintaining a series of record-receiving members in predetermined arrangement substantially parallel to said supporting part, a transverse back wall on said supporting part, a stop member for engaging one of said record-receiving members to limit movement of said record-receiving members in one direction, means for applying pressure in the opposite direction to hold said record-receiving members against said stop member, a plate member 70 adapted to cover the record-receiving portion of one of said record-receiving members, said plate member being detachably mounted on said supporting part, means on said supporting part for holding said stop member in engagement with said back wall, and means on said plate member adapted to hold said stop member in engagement with said supporting part, whereby said stop member is releasably 75 maintained on said record device.

18. In a record device, a record-supporting part for maintaining a series of record-receiving members in predetermined overlapping relation, side parts on said supporting part adapted to prevent lateral movements of said series on said supporting part, a detachable plate member adapted to cover the record-receiving portion of one of said members, said side parts of said device having apertures, and said plate member having pivot parts adapted to enter said apertures to permit swinging movements of said plate member relatively to said record-receiving members, and detachable means on 80 said device for maintaining said plate member in its pivotal relation to said apertures.

19. In a record device, a record-supporting part for maintaining a series of record-receiving members in predetermined overlapping relation, side parts on said supporting part adapted to prevent lateral movements of said series on said supporting part, a detachable plate member adapted to cover the record-receiving portion of one of said members, said side parts of said device having apertures, and said plate member having parts adapted to cooperate with said apertures to permit relative movement between said plate member and said record-receiving members, and detachable means on 85 said record device adapted to engage and removably secure said plate member parts in said relation to said apertures.

20. In a record device, a record-supporting part for maintaining a series of record-receiving members in predetermined overlapping relation, a detachable plate member adapted to cover the record-receiving portion of one of said record-receiving mem- 125

bers, said plate member having an attaching part, parts on said record device for receiving said attaching part, and detachable means having a part adapted to engage said plate member to maintain said attaching part of said plate in operative relation to said receiving parts on said record device.

21. In a record device, a record-supporting part for maintaining a series of record-receiving members in predetermined overlapping relation, a detachable plate member adapted to cover the record-receiving portion of one of said record-receiving members, said plate member having an attaching part, parts on said record device for receiving said attaching part, detachable means having a part adapted to engage said plate member to maintain said attaching part of said plate in operative relation to said receiving parts on said record device, and said detachable means being adapted to engage one of said record-receiving members to prevent movement of said series in one direction and having a part adapted to overhang said record-receiving member to maintain said member against unintentional removal from said supporting part, and means for applying pressure to said series of record-receiving members to hold said members against said detachable means.

22. In a device of the character described, means for supporting a plurality of record-receiving members in predetermined overlapping relation, a cover plate adapted to cover the record-receiving portion of the uppermost of said record-receiving members, means for detachably mounting said cover plate on said device, said cover plate being interchangeable with other cover plates of different lengths so that the uppermost record-receiving member will always have its record-bearing portion properly covered regardless of the length of said member.

23. In a record device, a record-supporting part for maintaining a series of record-receiving members in predetermined overlapping relation, side parts on said device adapted to prevent lateral movements of said series on said supporting part, a detachable plate member adapted to cover the record-receiving portion of one of said members, said side parts of said device having apertures,

and said plate member having pivot parts adapted to enter said apertures to permit swinging movements of said plate member relatively to said record-receiving members, means on said supporting part adapted to support said plate member when said plate member is moved to expose said record-receiving members, and detachable means on said device for maintaining said plate member in its pivotal relation to said apertures.

24. In a record device, a series of record-receiving members, a record-supporting part for maintaining said series of record-receiving members in predetermined overlapping relation, said members being adapted to swing to a position wherein their under faces are exposed, side parts on said device adapted to prevent lateral movements of said series on said supporting part, a detachable plate member adapted to cover the record-receiving portion of one of said members, said side parts of said device having apertures, and said plate member having pivot parts adapted to enter said apertures to permit swinging movements of said plate member relative to said record-receiving members, said plate member having a part adapted to slide on one of said record-receiving members to form anti-friction means therebetween when one or more of said record-receiving members are moved to expose the under face or faces thereof, and detachable means on said device for maintaining said plate member in its pivotal relation to said apertures.

25. In a card index tray adapted to support a plurality of record-bearing members in predetermined recumbent arrangement with the bodies of said record-bearing members substantially parallel with the bottom of said tray, a relatively fixed back stop detachably mounted in said tray and having a part for engaging a portion of one of said record-bearing members and retaining said members in the tray when they are pressed against said back stop, and a movable follower for applying pressure to said record-bearing members to hold them under compression against said back stop.
